COMBINATION WELL DRILLING RIG

Garlin E. Seals, Monahans, Tex.

Application March 12, 1936, Serial No. 68,498

6 Claims. (Cl. 255—3)

This invention relates to earth boring machinery and it has particular reference to equipment for drilling wells.

The principal object of the invention is to combine in a single unit, the elements of a standard or cable tool drilling assembly with the features of a rotary well drilling apparatus and to so combine the two rigs that certain elements of one will cooperate with certain elements of the other to accomplish unusual and improved results over conventional equipment, either standard or rotary. Moreover, the invention aims to improve upon present drilling equipment primarily by unitizing the elements of the assembly and mounting the units on skids whereby the elements may be separately loaded, hauled and reassembled without requiring unusual or special loading apparatus and conveyances.

Another object of the invention is to provide a novel type of base which serves all of the elements of the combination, and will accommodate the equipment irrespective of the size and capacity of the draw-works or the derrick, inasmuch as the base is constructed to be capable of adjustment.

Still another object of the invention is to provide an improved means for mounting and manipulating the Samson post which carries the walking beam. This particular type of mounting of the Samson post is novel in what it is superimposed on the draw-works for rotation in order that the operative end of the walking beam may be moved relative to the point of operations. Moreover, this feature provides for the mounting of the draw-works in line of operations instead of to one side, which would be necessary otherwise to accommodate the Samson post, and which would render its operation difficult and complex.

The invention further provides, in addition to a special type of derrick construction certain novel features of operation of the several elements making up the complete assembly as well as salient features of construction and operation of parts to become manifest as the description proceeds, taken in connection with the accompanying drawings wherein:—

Figure 1 is a side elevational view of a combination drilling rig constructed according to the present invention.

Figure 2 is a plan view of the apparatus.

Figure 3 is an elevational view in axial cross-section of the water cooled bull reel.

Figure 4 is a side elevation of the rotary draw-

works and Samson post, with portions of the base structure broken away.

Figure 5 is a detail view in perspective of the Samson post mounting.

Figure 6 is a complementary part of the 5 mounting shown in Figure 5.

Figure 7 is a side elevational view of the rotary drilling drum with clutch operating mechanism.

Figure 8 is a side elevational view of the rotary drilling drum with details of the brake operating mechanism. 10

Figure 9 is a phantom plan view of the complete apparatus, showing in solid lines the several control devices for the several elements of 15 the combination.

Figure 10 is a plan view of the novel form of base structure provided for the units of the combination.

Figure 11 is a side elevational view of a special 20 type of derrick used in combination with the invention with the combination rig shown operationally connected therewith.

Figure 12 is a fragmentary detail view, partly 25 in section of the ferrule or sleeve employed for holding sections of the derrick legs in axial alignment.

Figure 13 is a detail view in perspective and partly in section showing the manner of relatively bracing the legs of the derrick.

Figure 14 is a detail view of the dual control for the sand reel and 30

Figure 15 is a fragmentary detail view of the lever control for the bull reel shown in Figure 3. 35

In the drilling of wells, especially in regions where the formation is "cavey" it is desirable to employ the rotary method of drilling, yet when firmer formation is encountered in the same project, cable tools are preferred in view of the fact that hole can be made at much greater speed and at less cost. To effect interchange of the methods, separate sets of machinery, that is, rotary and cable tool, must be set up alternately as formation is encountered. This obviously 40 makes the cost prohibitive, hence it is not done, although highly desirable, since the time required to complete a well is reduced materially as is consequently the cost.

The foremost elements of the present invention are interrelated to the extent that they cooperate, one with the other so that combining of the two, heretofore separate methods of drilling is made possible with some added expense, which 55

is overcome by the reduction of cost in practical drilling operations.

Continuing with a more detailed description of the drawings reference is primarily made to Figures 1 and 2 in which 1 designates a portion of the I-beam base, supported upon sub sills 2 and held together by bolts 3. These bolts likewise secure the skids 4 to the I-beams 1 and upon which the elements of the combination are mounted for ease 10 in assembling, dismantling and transportation. Reference to the base structure, illustrated in greater detail in Figure 10 will be again made presently.

Mounted on the skids 4 at the rearmost end of 15 the base beams 1 is a bull reel or cable drum 5, and as apparent in Figure 2, this drum is provided with brake flanges 6 between which are situated brake bands 7. The shaft 8 of the drum is cored out at one end, as apparent in Figure 3 and the 20 brake drums 9 are hollow. An aperture 10 in the shaft allows water introduced into the end of the shaft through nipple 11, to enter one of the brake drums 9, from which it flows into the other brake drum through pipe 12, passing 25 through the drum 5. Drainage is provided for through the apertures in each drum 9, normally closed by plugs 13.

The gudgeons of drum 5 are journaled in bearing blocks or slides 14 superimposed upon the 30 standards 15, which in turn, are mounted upon the skids 4. In Figure 2 it will be observed that heavy springs 16 are arranged to bear against the shaft 8 near either end and thus absorb the shocks imposed upon the shaft by the cable on the drum 5.

35 One end of each brake band 7 is fixed while the other end is secured to the brake lever 17 (Figure 2). One end of the brake lever is turned upward and to this end is secured an operating rod 18, (Figures 2 and 9) which extends forwardly to 40 the driller's station and is provided with a hand lever 19. In order that the drum 5 may be provided with greater spooling capacity, a flat disc clutch is employed and is operated also from the driller's station in the manner shown in Figure 45 9, in which only a part of the clutch is shown to illustrate the connection therewith of the link 21. A bell crank 22 is pivoted at A and to one end thereof the link 21 is connected. A pull rod 23 is joined to the other end of the bell crank and 50 extends to the driller's station where a rod 24 is rotatably mounted in bearings 25. One end of rod 24 is bent in the manner shown and pivotally connected to the pull rod 23. The opposite end of rod 24 is formed into a hand lever 26 and at 55 a point accessible to the operator adjacent the rotary draw-works, which latter will be described presently.

A sprocket wheel 27 is mounted on the shaft 8 of drum 5 and is driven by a chain 28, surrounding this sprocket and a similar sprocket 29 on the band wheel shaft 30 which carries the band wheel 31.

The band wheel shaft 30 has a square boss 32 on its outer end, as apparent in Figure 1, about which 65 the hub 33 of the band wheel is secured. This hub is in two separable parts as is the band wheel 31 and these parts are secured together at the hub by bolts 34 and at the rim by bolts 35 which latter pass through ears 36 integral with the inside of the band wheel rim or flange. This makes for quick assembly and removal in the setting up and dismantling of the apparatus.

The band wheel shaft is of extra heavy type and is provided with three bearings 37 (Figure 2) 70 serving the front, center and rear points, the pur-

pose being to resist the strain ordinarily imposed upon this shaft by several drive chains operating various units of the assembly and to which reference will be again made later in the description.

Disposed between the band wheel shaft 30 and the drum 5, also on skids 4 is a sand reel 38, whose shaft is adjustable at either end. This adjustment is provided through bearings 39 at either end. Bolts 40 bear upon journal boxes (not shown) supporting the reel shaft and the shaft 10 may be thus aligned and maintained in alignment with the point of operations. This reel also is provided with a flat disc clutch 41, similar to clutch 20 of drum 5, in order to provide greater 15 spooling capacity, and is operated in the manner shown in Figure 9. A bell crank 42 is pivoted at b to the frame below the reel 38 and through a link 43, connection is made to the clutch disc 41, only a part of the clutch being shown in this figure. An operating rod 44 is operatively connected to the crank 42 and extends to the driller's station near the rotary draw-works. A hand lever 45 serves to actuate the rod 44 to operate the sand reel. The sand reel 38 has a dual control through the rod 44, that is to say, the clutch 41 as well as the single brake band 46 is actuated simultaneously by this rod. The detail of the connection between the rod 44 and the clutch and brake is shown in Figure 14 above Figure 9.

The rod 44 is pivotally connected, as shown with a plate or arm 47 which latter is centrally connected at c to one end of the brake band 46 of the sand reel 38. A link 48 connects the arm 47 to one end of bell crank 42. Obviously, a pull 35 on the rod 44 will displace the joint c of the arm 47 to effect frictional engagement of the band 46 with its drum and simultaneously the link 43 will be actuated by rotation of the bell crank 42 to move the clutch element 41 out of engagement 40 with its companion element (Figure 2) to release the sand reel from its driving element.

The sand reel 38 is driven from the band wheel shaft 30 through chain 49 and, by virtue of clutch 50 on the band wheel shaft, this drive can be controlled. To operate clutch 50 a rod 51 (Figure 9) having a hand lever or crank 52 on the end adjacent the driller's position, extends rearwardly and is similarly shaped on its other end to effect connection with a link 53. This link is also 50 connected to an element of the clutch 50 so that manipulation of the rod 51 will engage and disengage the elements of clutch 50 and thereby control the operation of the sand reel 38 in cases where it is desirable to operate the band wheel 55 shaft without operating the sand reel.

It is pointed out that individual and collective control of the elements of the combination, in a manner similar to that just described is highly desirable in actual performance, hence the provision of the group of clutches on the band wheel shaft 30. These clutches and their purpose will be described in the course of the description to follow.

It will be understood that the power for operating the assembly is supplied by a suitable power plant (not shown) and through a belt, chain or other drive, also omitted, the band wheel 31 is driven. It is obvious that by providing a split sprocket in place of the band wheel 31, a chain 70 drive may be used. Power thus derived drives the band wheel shaft 30 and through this medium, the bull reel 5 is driven and is controlled not only through the clutch 20 but also through the clutch 54 on the band wheel shaft 30 (Figure 2). Also, 75

the sand reel 38 is operated through chain 49, as explained, from the band wheel shaft and similarly, the line shaft 55 is actuated through chains 56 and 57. The purpose of the two drives for the line shaft 55 is to provide a speed differential. A large sprocket 58 on the band wheel shaft 30 is surrounded by the chain 56 which likewise surrounds sprocket 59 on the line shaft. A large sprocket 60 on the line shaft is surrounded by chain 57, which latter surrounds a smaller sprocket 61 on the band wheel shaft. Thus, by reversing the positions of certain clutch elements on the band wheel shaft, the speed of the line shaft may be varied.

15 With reference to the clutch elements on the band wheel shaft 30, a clutch 62 is provided for controlling the drive to the line shaft 55 through the chain 56. A rod 63 (Figure 9) is formed at one end adjacent the driller's station into a hand lever 64 and to the other end is connected a link 65, which in turn, is connected to and operates the clutch 62 when the hand lever 64 is operated. Thus, the drive to the line shaft 55 is put into operation or suspended at will. Similarly, a 20 clutch 66 serves to control the drive through chain 57 to the line shaft. A rod 67 (Figure 9) extends from the driller's station to the frame below the clutch 66 and through line 68, actuates the clutch when the rod 67 is operated.

25 The foregoing deals primarily with the standard or cable method of drilling wells. Reference is now made to the rotary elements and as such, the numeral 69 denotes a jack shaft which is driven from the band wheel shaft 30 through the medium of chain 70 (Figures 1 and 2). A clutch 71 (Figures 2 and 9) controls the drive through chain 70 and is actuated by rod 72, extending from the driller's station to the clutch and connection is made to the latter through link 73.

30 The rotary drilling table 74, (Figure 11) of conventional construction is driven from the jack shaft 69 through the medium of the chain 75, surrounding sprocket 76, mounted on one end of the jack shaft 69.

35 The peculiar construction of the rotary draw-works of the invention is of considerable importance, due to the fact that in order to interlock the cable with the rotary system of drilling, departure from conventionalities of both systems or 40 methods must be resorted to. In the first place, in order that the rotary drilling drum 77 may be properly aligned with the center of the derrick 78, (Figure 11) or point of operations, it is necessary that the Samson post 79, which carries the walking beam 80 (Figure 1) be also disposed so that alignment of the operative end of the walking beam with the well or derrick center is possible. To this end, and to insure thorough rigidity of the drum 77, its brake flanges or drums 81 are disposed adjacent the inside surfaces of the frame posts 82 (Figure 4) of the draw-works. The control clutches are disposed on the outside of the posts 82 to provide for the reinforcement obtained by so disposing the drilling drum 77. Greater 45 clearance is obtained by thus mounting the drilling drum and the arrangement provides for the proper placement of the walking beam mounting.

The walking beam mounting or Samson post 79 is situated on the headboard 83 (Figure 4) of the draw-works frame 82. A detailed illustration of this mounting is shown in Figures 5 and 6. A mounting plate or support 84, shown in dotted lines in Figure 2 is provided atop the Samson post 79, which has a complementary and relatively movable part 85 and of conforming disc shape.

The plate 84 has apertures 86 therein at spaced intervals which are in register with arcuate slots 87 in the plate 85. Bolts 88 are passed through the slots and apertures of the plates to secure the same against relative displacement when the walking beam 80 is in or out of operative position.

When the walking beam 80 is required to be in operative position, that is during operation of the cable system, the forward end (Figure 1) is disposed over the hole in the center of the derrick. In this position, bolts 88 are secured. However, when it is desired to place the rotary system in operation, these bolts are loosened and the walking beam is swung to one side of the derrick 78 so that it will not interfere with the rotary drilling operations. In so doing, plate 85 rotates on the base plate 84 and when the beam is disposed in inoperative position, bolts 88 are tightened to hold the beam against displacement.

20 Suitable reinforcement in the form of braces 89 and 90 are provided for rigidifying the Samson post 79 and a "headache" post on stop 91 (Figures 1 and 4) is disposed to prevent injury to the operators should the fulcrum pin of the walking beam 80 become sheared.

25 The walking beam 80 is operated through the medium of a pitman arm 92, connected by means of a stirrup 93, (Figure 1) to the walking beam and by means of a crank 94 (Figure 2) to the band wheel shaft 30. Obviously, rotation of the band wheel shaft will impart reciprocatory motion to the walking beam 80 and by suitable cable means, (not shown) the tools are operated in the well.

30 For ease in assembling and dismantling, the Samson post 79 is hinged at its base at 95 (Figures 1 and 4) to the head piece 83 of the draw-works. Inoperatively, the Samson post 79 lies downward on the draw-works but when moved to vertical or operative position, bolts 96 (Figure 1) secure the same in place. It is, of course necessary, in dismantling, to first disconnect the pitman arm 92 from the crank 94; then remove the walking beam 80 and disconnect the brace 89, by removing bolts 97 (Figure 1).

35 With especial reference to the rotary draw-works, it will be observed that the peculiar mounting of the Samson post 79 enables the draw-works to be brought near the center of the derrick without interference by the Samson post, which would, under ordinary conditions, be impractical if not impossible. The Samson post is disposed directly in line with the inside 40 brake wheel flange 87 of the draw-works.

45 The rotary drilling drum 77 of the draw-works is provided with two drives from the line shaft 55, as shown in Figure 2, in order to obtain two speeds. Chain 97 surrounds a sprocket on the line shaft 55 and a sprocket 98 on the shaft 99 of the drum 77. This drive is from a small to a large sprocket while the drive at the opposite end of shaft 99 is from a large to a small sprocket, the latter being disposed on the shaft 99 and identified by the numeral 100 and is surrounded by the chain 101, which likewise surrounds a larger sprocket 102 on the line shaft 55 (Figure 2).

50 In Figures 7 and 8, the rotary drum 77 is illustrated in detail. A clutch 103 is provided on either end of the drum shaft 99 and are alternately operated to effect change in drives and consequently the speeds. This change is effected by means of a rod 104 (Figure 7) whose 55

ends are pivotally connected at *d* to the arms of clutch forks 105. These forks engage the sliding parts of clutches 103 and when the rod 104 is longitudinally moved, the forks are pivotally displaced at *e* and effectually move the clutch elements into and out of engagement alternately.

To effect longitudinal movement of rod 104, a foot treadle 106 is provided and pivoted at *f* midway between its ends. The treadle has a slotted arm 107 extending upwardly therefrom, the slot receiving a pin 108 affixed to the rod 104. Obviously, depression of the treadle at either end will oscillate the arm 107, thereby moving the pin 108 and consequently the rod 104.

In Figure 8 is shown the means by which equalized pressure of the bands 109 of the drum 77 on the brake drums 81 is obtained. An arm 110 is pivoted at *g* below and midway between the ends of the drum to a bracket 111. The ends of the arm 110 carry bolts 112 which are adjustably connected to the free ends of the bands 109. The opposite ends of these bands 25 are looped and receive the bands 113 in the rod 114. The rod 114 is rotatably held to the skids 4 by straps 115 and one end of the rod is bent upward at 116 and terminates in a bifurcated end 117 to afford a locking means. By actuating the rod 114 by means of the lever 116, both bands 109 are contracted or expanded about their respective brake drums and when pressure is thus applied, the arm 110 will adjust itself to wear on either of the drums, or band linings. 35 When wear on one of the brakes is greater than that on the companion brake, it is a simple matter to take up this wear by adjusting the nuts on one of the bolts 112.

It has been stated that to properly combine the elements of the rotary and cable systems of drilling to avoid interference one with the other, it is necessary to consider the relative disposition of elements.

The invention therefore provides a base structure shown in detail in Figure 10, certain elements of which accommodate the derrick 78 while the remaining elements provide a support for the units of the rotary draw-works and cable drums. The important feature of this base lies 45 in ability of one section thereof to be moved relative to the companion section supporting the derrick. In this manner replacements such as the walking beam, drive chains and the like will not have to be made when a derrick of larger or 55 smaller floor area is used.

In Figure 10, the derrick supporting base is comprised of the longitudinal and transverse sills 2 forming the substructure. The longitudinal sills extend the full length of the base, that is, of the complete combination of units. 60 As a support for the derrick, I-beams 118 are disposed to form a square and the derrick legs are situated at each corner of the square, as shown at A, in dotted lines in Figure 10. These 65 I-beams are bolted to the sills 2 in the manner previously described, by bolts 3, (Figure 1).

The base structure for the units of the draw-works and cable units is arranged for movement relative to the center of the derrick and is composed of the longitudinal I-beams 1 and transverse I beam 1^a at the rear end of the assembly. These beams as are the beams 118, are supported upon the sills 2. The forward ends of the I-beams 1 are provided with a series of apertures 2^a in spaced relationship with the ends of

the beams which overlie one of the derrick supporting beams 118. Bolts 3^a are passed through apertures 2^a and through the beam 118 to hold the beams 1 rigid with respect to the derrick base. If the specifications for the derrick call for a smaller one than the size of the base provides for, the ends of beams 1 are moved toward the center of the derrick base and resecured. This procedure is of course reversed when a larger derrick is specified. It is clear therefore that no replacements or other adjustments are necessary.

A type of derrick peculiarly adapted to the present system is shown in Figures 11 to 13 inclusive and is comprised of hydraulic pipe leg sections 119, joined together by collars 120, through which bolts 121 are passed to hold the ends of the leg sections in place. This detail is shown in Figure 12. The girts 122 are preferably composed of I-beams secured in the manner shown in Figure 13 to the derrick legs.

The lower section of the derrick is hinged at 123 to the base and is raised first with the aid of the cable and drum assemblies. After the first section of the derrick is raised, it is steadied by four guy lines until the remaining parts of the derrick are moved into position and assembled.

Manifestly, the construction shown and described is capable of considerable change and modification and such changes and modifications are to be considered within the spirit and intent of the invention as fall within the scope and meaning of the appended claims.

What is claimed is:

1. A well drilling apparatus including in combination with a derrick, a base in sections, and a sub-base supporting said sections, one of said base sections supporting said derrick, said other section being arranged for movement toward and away from said first section, a rotary draw-works disposed forwardly of said movable base section, a plurality of cable drums spaced on said movable base section, skids secured to and supporting said rotary draw-works and cable drums on said movable base section, a walking beam, means for mounting said walking beam rotatably on said draw-works and means for controlling the operation of said draw-works and cable drums at a point adjacent said draw-works.

2. A well drilling apparatus including in combination with a derrick, a sectional base and a sub-base supporting said sectional base, whereby one of said base sections will be slidable relative to the other, a rotary draw-works, skids supporting said draw-works for sliding movement transversely of one of said base sections, a series of cable drums spaced from said draw-works, skids supporting said cable drums on said latter base section, a band wheel and shaft, means for driving said draw-works and cable drums from said band wheel shaft, a walking beam, a walking beam supporting post, means for rotatably mounting said post on said draw-works, means for actuating said walking beam from said band wheel shaft and means to control the operation of said draw-works and cable drums from a point adjacent said draw-works.

3. A well drilling apparatus including in combination with a derrick, a base for said derrick, an auxiliary base movable relative to said derrick base and securable thereto in adjusted positions in accordance with the area of the derrick, a band wheel and a band wheel shaft, a frame therefor, a rotary drilling drum disposed adjacent the point of securement between said base

- sections, a frame therefor, a series of cable drums spaced rearwardly of said drilling drum, means for transmitting rotary movement to said rotary drilling drum and said cable drums from said 5 band wheel shaft, spaced skid members supporting the frames of said rotary drilling drum, cable drums and said band wheel shaft, a walking beam, a mounting therefor, means for rotatably securing said mounting on the frame of said 10 rotary drilling drum whereby to effect movement of said walking beam into and out of operative position and means for operating said walking beam from said band wheel shaft.
4. In a well drilling apparatus, a derrick, a base 15 in sections, one of said sections being stationary and supporting said derrick, a series of cable operated drums supported on the other of said sections, frames therefor, a band wheel and shaft, skid means for mounting said drum frames 20 and band wheel shaft slidably on said latter base section, a walking beam and a mounting therefor, means for rotatably supporting said walking beam mounting on the frame of one of said drums, means for driving said drums and said 25 walking beam from said band wheel shaft and means for adjusting said latter base section relative to the derrick supporting section to effect operative alinement of said walking beam with the center of said derrick.
- 30 5. In a well drilling apparatus in combination with a derrick and a rotary table, a base in sec-
- tions, one of which is movable relative to the other, the stationary of said sections being arranged to support said derrick, a rotary draw-works disposed on the movable section of said base, having a jack shaft operatively connected with said rotary table, a series of cable drums, a common drive shaft for said drums and said draw-works, a frame for said draw-works and said drums, each of said frames being mounted for individual placement and displacement relative to said movable base section, a walking beam and a mounting post therefor, means for mounting said post rotatably on said draw-works frame for movement relative to the center of said derrick and means for securing said movable base 15 section at adjusted positions relative to its companion base section.
6. In a well drilling apparatus, in combination with a derrick and a rotary table, a base in sections, one of which is arranged to support said 20 derrick, the other being displaceable relative to the derrick supporting section, a rotary draw-works removably mounted on the displaceable section of said base, a walking beam, a mounting therefor disposed rotatably on said draw-works, 25 a series of cable drums also removably mounted on said displaceable base section and a common drive shaft for said draw-works, walking beam and said cable drums.

GARLIN E. SEALS. 30
